*Primary Examiner—Brian N. VinsonAttorney, Agent, or Firm—Karl V. Sidor[57] CLAIM

I claim the ornamental design for the toilet tissue dispenser, as shown and described.

DESCRIPTION

FIG. 1 is a front elevation of the toilet tissue dispenser showing my new design;

FIG. 2 is a left side elevation thereof;

FIG. 3 is a right side elevation thereof;

FIG. 4 is a top plan view thereof;

FIG. 5 is a bottom plan view thereof;

FIG. 6 is a rear elevation thereof; and,

FIG. 7 is a right front perspective view.
